CLAIM

The ornamental design for data processing system peripheral equipment, as shown and described.

DESCRIPTION

FIG. 1 is a perspective view of a first embodiment of data processing system peripheral equipment in accordance with our design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof; and

FIG. 7 is a bottom plan view thereof;

FIG. 8 is a perspective view of a second embodiment of data processing system peripheral equipment in accordance with our design;

FIG. 9 is a front elevational view thereof;

FIG. 10 is a top plan view thereof;

FIG. 11 is a right side elevational view thereof;

FIG. 12 is a left side elevational view thereof;

FIG. 13 is a rear elevational view thereof; and,

FIG. 14 is a bottom plan view thereof.

The broken lines represent portions of the data processing system peripheral equipment that form no part of the claimed design.
